REVERSIBLE HOUSE COAT

Lawrence J. Nachman, New York, N.Y., assignor to
Swirl, Inc., Easley, S.C., a corporation of South
Carolina

Filed Feb. 8, 1965, Ser. No. 83,721

Term of patent 14 years

(Cl. D3—26)

FIG. 1.

FIG. 2.

FIG. 3.

FIG. 4.

FIG. 1 is a front elevational view of a reversible house coat showing the front of one side of my new design;

FIG. 2 is a rear elevational view thereof;

FIG. 3 is a front elevational view of the reverse side of the reversible house coat shown in FIG. 1; and

FIG. 4 is a rear elevational view thereof.

The characteristic feature of my design resides in the combination on the reversible house coat disclosed of the particular shape and arrangement of the pockets and patches on the front and back of each face thereof substantially as shown.

I claim:

The ornamental design for a reversible house coat, as shown and described.
